UNITED STATES PATENT OFFICE.

JOSEPH GREVEN, OF CHICAGO, ILLINOIS.

MEANS FOR TRUING ALIGNED BEARINGS.

Application filed October 28, 1920, Serial No. 420,116. Renewed September 5, 1922. Serial No. 586,355.

To all whom it may concern:

Be it known that I, JOSEPH GREVEN, a citizen of the United States, and a resident of the city of Chicago, county of Cook, and State of Illinois, have invented certain new and useful Improvements in Means for Truing Aligned Bearings, of which the following is a specification.

My invention relates to means for truing aligned bearings and it has for its principal object the provision of new and improved means for effecting mechanically the necessary scraping of a plurality of white metal bearings aligned in working position in a machine frame for insuring a proper revoluble support for a shaft.

Other objects will appear hereinafter.

The invention consists in the combinations and arrangements of parts hereinafter described and claimed.

The invention will be best understood by reference to the accompanying drawings forming a part of this specification, and in which,

Fig. 1 is a top plan view of my improved mechanism, and showing in dotted lines a frame provided with a plurality of bearings upon which work is to be done;

Fig. 2 is an enlarged detail view, being substantially a section taken on line 2—2 of Fig. 1;

Fig. 3 is an enlarged detail view, being a section taken on line 3—3 of Fig. 1;

Fig. 4 is a face view of the driving mechanism, but with the driving pulley removed and with the parts at a different angle from that of the showing of Fig. 1;

Fig. 5 is a central vertical section, being taken substantially on line 5—5 of Fig. 4;

Figs. 6, 7 and 8 are detailed side views of elements of my improved mechanism;

Fig. 9 is a top plan view of one of the brackets by which the boring bar of my mechanism is held in position;

Fig. 10 is an end view of the structure shown in Fig. 9 as seen from the left in said figure;

Fig. 11 is an end view of the structure shown in Fig. 9 as seen from the right in said figure;

Fig. 12 is an enlarged detail view, being substantially a section taken at line 12—12 of Fig. 9;

Fig. 13 is an enlarged detail view, being

substantially a section taken at line 13—13 of Fig. 9;

Fig. 14 is an end view of the connecting rod shown in Fig. 13 as seen from the left in said figure;

Fig. 15 is a face view of the plate shown in Fig. 11 but with the co-operating parts removed therefrom; and

Fig. 16 is a diagrammatical view showing the method of driving the operating parts.

Referring to the drawings, 20 indicates a machine frame provided with a plurality of semi-cylindrical bearings 21 which are mounted in alignment with each other and which are to be scraped for perfecting the alignment for the proper working support of a straight shaft. In the construction shown, the frame 20 is in the form of the cover plate forming a part of the axle housing of an automobile engine, the bearings 21 being the ordinary brass bearings provided with facings of Babbitt or other suitable bearing metal.

A plurality of brackets 22 are used adjustably mounted upon the frame 20 by means of clips 23 which are held in position by bolts 24 as is best shown in Fig. 10. The brackets 22 are so arranged with respect to the frame with which they are to be used as to insure that the working parts carried by the bracket as hereinafter described may be adjusted to the desired position with respect to the axis about which bearings 21 are aligned.

As is clearly shown in Fig. 10, each of the brackets 22 is provided with a plurality of bearing plates 25 slidably mounted thereon in radially adjustable positions, being adapted to be held in adjusted position by means of machine screws 26 working in slots 27 of the bearing plates 25. The adjustment of the bearing plates 25 is further controlled by means of set-screws 28 which are mounted in the bracket and bear at their inner ends against the outer ends of the bearing plates. As is best shown in said Fig. 10, a shaft or bar 29 is held in position upon the frame 20 by means of the brackets 22, the bearing plates 25 being adjustable for controlling to a nicety the position of the shaft for centering the shaft to bring its axis to correspond exactly with the axis of the bearings 21. The bearing plates 25 are to be adjusted with respect to the

shaft or bar 29 so that the shaft is free to rotate and is free to move longitudinally with respect to such plates, but is held very firmly against any lateral movement.

- 5 For effecting a rough preliminary centering of the bar 29 upon the frame 20, I have provided a gear 30 fixedly mounted upon one end of the bar in position to mesh with a gear 31 carried by the frame 20, the 10 gear 31 being adapted to mesh with a suitable driving gear carried by the shaft to be supported by the bearings 21. As will be readily understood, by providing upon the bar 29 a gear of the same type as that later 15 20 25 30 35 40 45 50 55 60 65 70 75 80 85 90 95 100 105 110 115 120 125 130 135 140 145 150 155 160 gear 62 fixedly mounted upon the sleeve 43. The plate 58 is provided at its outer edge with a flange 63 extending about the gearing above described. In the construction shown the gearing connecting the shaft 29 with the sleeve 43 is adapted to reduce the speed of rotation by a ratio of approximately 9 to 1, and the threads upon the sleeve 43 are designed to be preferably 10 sixty to an inch. It is evident accordingly that the cutting tools 34 are given between five hundred and six hundred revolutions for each inch of movement longitudinally of the bar. It is accordingly apparent that 15 in the use of my apparatus very accurate results may be obtained inasmuch as an exceedingly light cut is made by each of the cutting tools 34 at each revolution. Inasmuch as the tools 34 are working in soft 20 metal and with a very slow rate of advance as above described, the bearings 21 are adapted to be scraped with exceedingly great accuracy, the strength and stiffness of the bar 29 being sufficient to prevent any 25 tendency for the bar to give laterally.

While I have illustrated and described the preferred form of construction for carrying my invention into effect, this is capable of variation and modification without departing 30 from the spirit of the invention. I, therefore, do not wish to be limited to the precise details of the construction set forth, but desire to avail myself of such variations and modifications as come within the scope of 35 the appended claims.

Having described my invention, what I claim as new and desire to secure by Letters Patent, is:—

1. The combination of a bar, means for 40 mounting said bar revolvably in centered position with respect to a plurality of substantially aligned bearings fixed in a machine frame, cutting tools carried by said bar adjacent to said bearings respectively, means for rotating said bar, a screw-threaded member revolvably mounted with respect to said bar, means for driving said member from said bar, and means radially disposed about said screw-threaded member adapted by engagement therewith to move the bar longitudinally for carrying said cutting tools into operative engagement with said bearings for truing the alignment of the bearings, substantially as described.

2. The combination of a bar, means for 55 mounting said bar revolvably in centered position with respect to a plurality of substantially aligned bearings fixed in a machine frame, cutting tools carried by said bar adjacent to said bearings respectively, means for rotating said bar, a screw-threaded member revolvably mounted with respect to said bar, means for driving said member from said bar, and an adjustable bracket 60 mounted on said machine frame and pro-

vided with radially disposed screw-threaded part adapted by engagement with the screw threads of said member to move the bar longitudinally for carrying said cutting tools into operative engagement with said 70 bearings for truing the alignment of the bearings, substantially as described.

3. The combination of a bar, means for mounting said bar revolvably in centered position with respect to a plurality of substantially aligned bearings fixed in a machine frame, cutting tools carried by said bar adjacent to said bearings respectively, means for rotating said bar, a screw-threaded member revolvably mounted with respect to said bar, means for driving said member from said bar, a bracket fixedly mounted on said machine frame, and a plurality of radially adjustable bearing plates carried by said bracket and screw-threaded on their inner ends adapted by engagement with the screw threads of said member to move the bar longitudinally for carrying said cutting tools into operative engagement with said 80 bearings for truing the alignment of the 85 bearings, substantially as described.

4. The combination of a bar, means for mounting said bar revolvably in centered position with respect to a plurality of substantially aligned bearings fixed in a machine 95 frame, cutting tools carried by said bar adjacent to said bearings respectively, means for rotating said bar, a sleeve revolvably mounted on said bar but held against longitudinal movement with respect thereto, a plate revolvably mounted with respect to said sleeve, means for holding said plate against rotary movement, gearing mounted on said plate and connecting said sleeve with said bar, screw threads on the outer face of said sleeve, and means fixedly mounted on said frame adapted by engagement with said screw threads to move the bar longitudinally for carrying said cutting tools into operative engagement with said 100 bearings for truing the alignment of the bearings, substantially as described.

5. The combination of a bar, a plurality of brackets, means for securing said brackets in fixed position upon a machine frame in spaced relation thereon substantially in alignment with respect to a plurality of bearings fixed on the frame, means for giving said bar a snug revoluble mounting on said brackets in centered position with respect to said bearings, cutting tools carried by said bar adjacent to said bearings respectively, a screw-threaded member revolvably mounted with respect to said bar, and held against longitudinal movement with 110 respect thereto, means for rotating said bar, means actuated by the rotation of said bar for rotating said member, and means carried by one of said brackets adapted by co-operation with said screw-threaded member 115 120 125 130

for moving the bar longitudinally for carrying the cutting tools into operative engagement with the bearings for truing the alignment of the bearings, substantially as 5 described.

6. The combination of a bar, a plurality of brackets, means for securing said brackets in fixed position upon a machine frame in spaced relation thereon substantially in 10 alignment with respect to a plurality of bearings fixed on the frame, means for giving said bar a snug revoluble mounting on said brackets in centered position with respect to said bearings, cutting tools carried 15 by said bar adjacent to said bearings respectively, a sleeve revolubly mounted on said bar but held against movement longitudinally with respect thereto, means for rotating the bar, gearing connecting said 20 sleeve with said bar, screw threads on the outer face of said sleeve, a bracket fixedly connected with one of said first named brackets, and a plurality of radially adjustable bearing plates carried by said last mentioned bracket and screw-threaded on their 25 inner ends adapted by engagement with the screw threads of said sleeve to move the bar longitudinally for carrying said cutting tools into operative engagement with said 30 bearings for truing the alignment of the bearings, substantially as described.

7. The combination of a bar; means for mounting said bar revolubly in centered position with respect to a plurality of substantially aligned bearings fixed in a machine frame; cutting elements carried by said bar; means for rotating said bar; a screw threaded sleeve revolubly mounted with respect to said bar; a bracket mounted 40 on one of said mounting means; a flanged plate mounted on said screw threaded sleeve; means mounted on said plate and engaging said bracket for holding said plate against rotary movement; a plurality 45 of adjustable members carried by said bracket and screw threaded on their inner ends adapted by engagement with said screw-threaded sleeve to move the said bar longitudinally for carrying said cutting elements in operative engagement with said 50 bearings for truing the alignment of the said bearings, substantially as described.

8. The combination of a bar, a plurality of brackets, means for securing said brackets in fixed position upon a machine frame in spaced relation thereon substantially in alignment with respect to a plurality of bearings fixed on the frame, means for giving said bar a snug revoluble mounting on 55 said brackets in centered position with respect to said bearings, cutting tools carried by said bar adjacent to said bearings respectively, a screw-threaded member revolubly mounted with respect to said bar, 60 and held against longitudinal movement 65

with respect thereto, means for rotating said bar, means actuated by the rotation of said bar for rotating said member, an adjustable bracket mounted on one of said brackets; and adjustable means carried by 70 said bracket adapted by co-operation with said screw-threaded member for moving the bar longitudinally for carrying the cutting elements into operative engagement with the bearings for truing the alignment of the 75 said bearings, substantially as described.

9. The combination of a bar, a plurality of brackets, means for securing said brackets in fixed position upon a machine frame in spaced relation thereon substantially in 80 alignment with respect to a plurality of bearings fixed on the frame, means for giving said bar a snug revoluble mounting on said brackets in centered position with respect to said bearings, cutting tools carried 85 by said bar adjacent to said bearings respectively, a screw-threaded member revolubly mounted with respect to said bar, and held against longitudinal movement with respect thereto, means for rotating 90 said bar, means actuated by the rotation of said bar for rotating said member, an adjustable bracket mounted on one of said brackets; a plate mounted on said sleeve member; a laterally extending arm carried 95 by said plate and engaging said adjustable bracket, holding said plate against rotary movement; and a plurality of radially extending plates carried by said bracket and screw-threaded on their inner ends, adapted 100 by engagement with said screw-threaded member to move the bar longitudinally for carrying said cutting tools into operative engagement with said bearings for truing the alignment of the said bearings, substantially as described.

10. A boring machine of the class described, comprising the plurality of brackets removably mounted on the frame of a machine; a longitudinally removable boring bar revolubly mounted on said brackets substantially in alignment with respect to a plurality of bearings on said frame; cutting elements imbedded in said bar and projecting laterally therefrom; means for rotating said bar; a bracket mounted on one of the foresaid brackets; a screw-threaded sleeve mounted on said bar; means for rotating said sleeve by a rotary movement of said bar; a plate mounted on one end of said screw threaded sleeve; a laterally extending arm mounted on said plate and slidably engaging a slot in said second mentioned bracket for holding said plate against rotary movement; and radially adjustable plates mounted on said second mentioned bracket and screw-threaded on their engaging faces adapted by engagement with said screw-threaded sleeve to move the said bar longitudinally for carrying 120 125 130

said cutting tools in operative engagement with said bearings for truing the alignment of the said bearing, substantially as described.

5 11. In combination with a machine frame having a plurality of substantially aligned bearings; cutting means revolvably mounted on said frame adjacent to said bearings respectively; a drive member revolvably 10 mounted with respect to said cutting means; and radially extending adjustable means disposed about said member adapted by engagement therewith to move said cutting means into operative engagement with 15 said bearings for truing the alignment of the bearings, substantially as described.

12. The combination with a plurality of substantially aligned bearings fixedly mounted in a machine frame, of a rotatable 20 boring bar removably mounted on said frame and operatively engaging said bearings; means for rotating said bar; and adjustable means projecting into contact with said bar for moving the bar into operative engagement 25 with said bearings, substantially as described.

13. The combination with a plurality of substantially aligned bearings fixedly mounted in a machine frame, of a rotatable 30 boring bar removably mounted on said frame; cutting elements adjustably mounted on said bar adjacent to said bearings re-

spectively; a screw-threaded member revolvably mounted with respect to said bar; and radially adjustable screw-threaded bearings 35 disposed about said member adapted upon engagement therewith to move said cutting elements into operative engagement with said bearings for truing the alignment of the bearings, substantially as described. 40

14. The combination with a plurality of substantially aligned bearings fixedly mounted in a machine frame, of a rotatable bar mounted on said frame; cutting elements mounted on said bar adjacent to said 45 bearings respectively; a screw-threaded member revolvably mounted with respect to said bar; and adjustable bearing members radially disposed about said screw-threaded member, said radially disposed members being provided with screw-threaded engaging surfaces adapted upon engagement with said screw-threaded member to move said cutting elements into operative engagement with said bearings, substantially as de- 50 55 scribed.

In testimony whereof I have signed my name to this specification in the presence of two subscribing witnesses.

JOSEPH GREVEN.
